CLAIM

The ornamental design for a stringed instrument plectrum, as shown and described.

DESCRIPTION

FIG. 1 is a front perspective view of a stringed instrument plectrum showing my design;

FIG. 2 is a top plan view thereof;

FIG. 3 is a front elevational view thereof, the rear elevational view thereof being a mirror image;

FIG. 4 is a right side elevational view thereof, the left side elevational view thereof being a mirror image; and,

FIG. 5 is a bottom plan view thereof.
